UNITED STATES PATENT OFFICE.

SAMUEL PATTERSON AND JOHN W. WISEMAN, OF GONZALES COUNTY, TEXAS, ASSIGNEES OF ONE-THIRD TO OLIVER T. PAYNE, OF LAVACA COUNTY, TEXAS.

SIGNAL-LOCK FOR MAIL-BOXES.

No. 875,841.

Specification of Letters Patent.

Patented Jan. 7, 1908.

Application filed March 25, 1907. Serial No. 364,292.

To all whom it may concern:

Be it known that we, SAMUEL PATTERSON and JOHN W. WISEMAN, citizens of the United States, residing in the county of 5 Gonzales and State of Texas, have invented certain new and useful Improvements in Signal-Locks for Mail-Boxes, of which the following is a specification.

Our invention relates to devices for locking the signals used on mail boxes to indicate the presence or absence of mail matter in the box and is especially adapted for use with boxes used in rural mail service and has for its object the provision of a lock that can be 15 applied to the boxes already in use as well as being manufactured as part of the box, that can be operated only from the inside of the box, and that will require but one hand to operate the lock and signal.

20 The construction and operation of our invention will be described in detail hereinafter and illustrated in the accompanying drawings in which—

Figure 1 is a view of a conventional mail box partly broken away and showing our improved signal lock in position, Fig. 2, a plan view of the lock partly in section, and Fig. 3, a longitudinal sectional view of the latch.

30 In the drawings similar reference characters indicate corresponding parts throughout the several views.

A indicates a mail box of any selected construction and B a signal therefor having its 35 staff C bent at right angles as shown at D and inserted through a hole in the side of the box A. The portion D is formed with a rectangular shoulder E and a threaded end F.

G indicates a plate secured to the inside of 40 box A, the portion D extending through said plate and having secured to its rectangular shoulder E a slotted latch guide H carrying a latch I pivotally secured thereto, and J a leaf spring to normally hold latch I depressed, said spring J being held in position 45 by means of a nut K secured on the threaded end F.

The edge of plate G is the segment of a circle of which the hole through which the portion D extends is the center and is formed 50 with an overhanging portion L to receive the end of latch guide H and is provided with notches M to receive the latch I to hold the signal B in an adjusted position.

It will be understood that as the latch I 55 can be reached only when the box is open the signal can not be changed by anyone not having access to the box. It will also be understood that as the latch guide H is secured to the end of signal staff C and swings 60 therewith that the signal can be operated with one hand.

Having thus described our invention what we claim is—

1. A signal lock for mail boxes comprising 65 in combination with a mail box having a hole therein, a signal having a staff inserted through said hole, a slotted latch guide secured to the end of said staff, a latch pivotally secured to said guide, and means to engage 70 said latch to hold the signal in an adjusted position, substantially as shown and described.

2. A signal lock for mail boxes comprising in combination with a mail box having a hole 75 therein, a plate secured to the inside of the box and having a hole to register with the hole in the box, said plate being provided with a segmental overhanging portion with notches therein, a signal having a staff inserted through the hole in the box and in the plate, a slotted latch guide secured to the end of the signal staff, and a spring actuated latch pivotally secured to said guide and adapted to engage the notches in the overhanging portion aforesaid, substantially as 80 shown and described.

In testimony whereof we hereto affix our signatures in the presence of two witnesses.

SAMUEL PATTERSON.
JOHN W. WISEMAN.
